Fig.1.

This diagram illustrates a telephone system architecture with the following components and connections:

- Sub** (10) is connected to **Subs Line Circuit** (12) and **Called Unit** (16).
- Subs Line Circuit** (12) is connected to **Calling Unit** (15) and **Called Unit** (16).
- Called Unit** (16) is connected to **Metering & Release Junction** (19), **Go Speech Junction** (17), **Return Speech Junction** (18), **Calling Junction** (25), **Identification Junction** (25'), **Busy Junction** (20), and **ALLOTTER** (24).
- Calling Unit** (15) is connected to **Metering & Release Junction** (19), **Go Speech Junction** (17), **Return Speech Junction** (18), **Calling Junction** (25), **Identification Junction** (25'), **Busy Junction** (20), and **ALLOTTER** (24).
- ALLOTTER** (24) is connected to **REGISTER** (23).
- REGISTER** (23) is connected to **MCU PULSE GENERATOR** (26).
- MCU PULSE GENERATOR** (26) is connected to **HIGH FREQUENCY PULSE GENERATOR** (14).
- MCU PULSE GENERATOR** (26) is connected to **Td₀**, **Td₁**, **Td₂**, **Td₃**, **Td₄**, **Td₅**, **Td₆**, **Td₇**, **Td₈**, **Td₉**, **Td₁₀**, **Td₁₁**, **Td₁₂**, **Td₁₃**, **Td₁₄**, **Td₁₅**, **Td₁₆**, **Td₁₇**, **Td₁₈**, **Td₁₉**, **Td₂₀**, **Td₂₁**, and **Td₂₂**.
- High Frequency Pulse Generator** (14) is connected to **Td₀**, **Td₁**, **Td₂**, **Td₃**, **Td₄**, **Td₅**, **Td₆**, **Td₇**, **Td₈**, **Td₉**, **Td₁₀**, **Td₁₁**, **Td₁₂**, **Td₁₃**, **Td₁₄**, **Td₁₅**, **Td₁₆**, **Td₁₇**, **Td₁₈**, **Td₁₉**, **Td₂₀**, **Td₂₁**, and **Td₂₂**.
- Sub** (11) is connected to **Subs Line Circuit** (13) and **Called Unit** (16).

TELECOMMUNICATION SYSTEMS EMBODYING
AUTOMATIC EXCHANGES

Maurice Moise Levy, Ottawa, Ontario, Canada, assignor
to The General Electric Company Limited, London,
England

Application November 24, 1951, Serial No. 257,991

4 Claims. (Cl. 179—18)

The present invention relates to telecommunication systems embodying automatic exchanges.

In copending U. S. Patent application No. 247,072 there is described an improved automatic exchange in which a fixed plurality of communication channels is provided. Calling apparatus responsive to an initial calling signal such as a D. C. signal transmitted when a telephone subscriber lifts a telephone handset prior to dialling the number of another subscriber, selects a free one of the aforesaid communication channels. Means are provided whereby, in operation, further calling signals, such as dialling impulses, are then applied in the exchange to transmit to the terminal equipment of the called subscriber an identification signal identifying the selected one of the communication channels. Apparatus is provided to identify the channel indicated by the identification signal and to connect the called subscriber to the identified channel.

In copending U. S. patent application No. 257,786 an automatic exchange is described similar to that in application No. 247,072. The means described in application No. 257,786 for transmitting the signal identifying the seized communication channel differ from those described in application No. 247,072 and comprise a group of low grade channels, one channel for each subscriber on the exchange. It is preferred to use interlaced pulse trains to provide the low grade channels, and the identification signal consists of a coded group of pulses transmitted during each pulse interval in the low grade channel associated with the called subscriber.

The coded group of pulses is applied to call the subscriber being called, and to set into operation suitable apparatus for establishing a connection with the communication channel identified by the coded group of pulses.

In order to ensure an adequate speed of operation, however, it may be found necessary to make the pulses in the coded group of a width so small as to cause difficulties in design. These difficulties arise from the fact that the energy contained in the pulses is small.

An object of the present invention is to provide improved apparatus whereby the aforesaid difficulties can be overcome.

According to the present invention, an automatic exchange comprises a number of low grade calling channels equal to the number of stations connected to the exchange, a number of low grade identification channels equal to the number of calling channels, a number of high grade channels substantially less than the number of calling channels, calling apparatus responsive to an initial calling signal from a first station to seize a free one of the high grade channels, a register device responsive to further calling signals from the first station, and representative of the number of a second station, to transmit a calling signal in a predetermined one of the calling channels and an identification signal in a corresponding one of the identification channels, the identification signal being representative of the number of the seized high grade channel, and apparatus adapted in response to the calling and identification signals to connect the terminal equipment of the

2

second station to the identified high grade channel. A low grade channel is a channel having a relatively small bandwidth whereas a high grade channel is a channel having a relatively large bandwidth. When a free high grade channel is seized it is meant that a free high grade channel is found, a connection established therewith and further stations are prevented from using this channel for establishing another call until this channel is released.

After communication has been established the register device may be released for use in making a further call. The maximum number of calls which can be made simultaneously is, therefore, equal to the number of registers provided. This number will, of course, be determined by calculation of the expected load.

The calling, identification, and high grade channels are all preferably provided by interlaced pulse trains. The calling channels may for example be 2,000 in number and the pulses used for each calling channel may have a recurrence frequency of say one pulse per second. The identification channels may be provided by pulses of the same frequency, and the high grade channels may be 100 in number and each one provided by pulses of a recurrence frequency of 8,000 pulses per second. The identification signal may be provided by a coded group of say two pulses.

It will be appreciated that the calling pulse will be much broader than the pulses in the coded group constituting the identification signal. The identification signal does not, however, have to be used to control either calling apparatus or line finders and hence the design difficulties previously referred to are alleviated.

The invention will now be described, by way of example with reference to the accompanying drawings, in which

Figure 1 is a block schematic diagram of one embodiment of the invention;

Fig. 2 is a circuit diagram of a subscriber's line circuit shown in block form in Fig. 1;

Fig. 15 is a diagram showing in more detail the M. C. D. U. pulse generator shown in block form in Fig. 1;

Fig. 16 is a further explanatory diagram;

Fig. 17 is a diagram of a gate circuit; and

Fig. 18 is a diagram showing the manner in which the drawings of Figs. 2-12, 14, 15 and 17 are interconnected to provide the arrangement shown in block form in Fig. 1.

Referring to Figure 1 this is a block schematic diagram of an automatic exchange suitable for use with 2,000 subscribers. Of the 2,000 subscribers' stations connected

to the exchange, one is shown at 10 and another at 11, the station 10 being terminated in the exchange at "sub's line circuit" 12 and the station 11 being terminated at the "sub's line circuit" 13. The "sub's line circuits" will be described later.

The exchange comprises a group of 100 high grade pulse communication channels. This group of channels is provided by means including a pulse generator 14 adapted to generate pulses suitable for combination to provide the 100 channels time-interlaced at a pulse repetition frequency of 8,000 pulses per second in each channel. The 100 channels are terminated by 100 "calling units" respectively of which one is shown at 15. 100 "called units" terminate the other ends of the channels respectively when in use, one of the called units being shown at 16. The calling and called units will be described later. Signals between the calling and called units pass through a "Go speech junction" 17, a "Return speech junction" 18 or a "Metering and release junction" 19 as the case may be. In the event of a called subscriber being engaged, a "busy signal" is transmitted to the calling subscriber by way of a "busy junction" 20 as will be described later.

For use in establishing calls between subscribers a number of allotters 24 and registers 23 are provided together with a calling junction 25, an identification junction 25' and two further pulse generators 21 and 26, examples of which will be described later.

Assuming the subscriber at station 10 to be calling the subscriber at station 11, the first operation occurs in the sub's line circuit 12. This contains a finder which finds a free calling unit 15. An allotter 24 then comes into operation and allots a register 23 to the calling unit 15.

By means of the allotter and a finder in the register the calling unit found by the sub's line circuit 12 is connected to the allotted register 23 as will be described later. A dialling tone is then automatically transmitted to the calling subscriber.

The output of the pulse generator 21 is in the form of a recurring sequence of twenty pulses which for convenience will be divided into two groups of ten each. The first ten pulses in each sequence will be referred to collectively as the *d'* pulses and the second ten as the *u'* pulses. The ten *d'* pulses will be referred to individually as pulses *d'*₀ to *d'*₉ respectively and appear at the terminals *Td'*₀ to *Td'*₉ of the generator 21. The ten *u'* pulses will be referred to individually as pulses *u'*₀ to *u'*₉ and appear at terminals *Tu'*₀ to *Tu'*₉ of the generator 21.

Each calling unit 15 is connected to one of the terminals *Td'*₀ to *Td'*₉ and to one of the terminals *Tu'*₀ to *Tu'*₉ of the generator 21 different ones of the calling units being connected to different pairs of the terminals *Td'* and *Tu'*. Thus each calling unit is identified by a different pair of *d'* and *u'* pulses and, as will be described later, the pair of *d'* and *u'* pulses identifying the calling unit seized by a calling subscriber's line circuit is transmitted to the called subscriber's line circuit to identify the high grade channel on which communication is to be established.

When the calling subscriber hears the dialling tone and dials the number of the called subscriber, the dialling pulses are transmitted through the line circuit 12, and the seized calling unit 15 to the allotted register 23. In the register the four sets of dialling pulses are stored on four uniselectors as will be described later. Four groups of ten pulses each, which will be referred to as the M, C, D and U pulses, are applied to the four uniselectors in the register from the pulse generator 26. Thus the uniselectors in the register select one pulse from each of the four groups of recurring pulses applied thereto and it is arranged that these four selected pulses are combined to form a recurring output pulse which occurs in one recurring channel interval in a recurring sequence of 2,000 channel intervals. The sequence may recur, for example, at the rate of one per second and the 2,000 chan-

nels constitute a group of low grade communication channels.

The recurring output pulse to be referred to as the calling pulse from the register is passed to the calling junction and, in addition, is used as a gating pulse and permits the recurring pair of *d'u'* pulses identified with the seized calling unit to pass to the identification junction 25' only in the low grade channel interval determined by the gating pulse.

10 The outputs from the calling and identification junctions are applied to all subscriber's line circuits. These circuits have gating pulses applied thereto, however, from the pulse generator 26, the gating pulses applied to each subscriber's line circuit being in the channel whose number corresponds to the subscriber's number on the exchange. Thus the only subscriber's line circuit to respond to a calling pulse appearing at the output of the calling junction is that one whose gating pulse corresponds to the number dialled.

15 The called subscriber's line circuit then hunts for a free called unit and when a free called unit is found this unit functions, as will be described later, to select appropriate pulses from the output of the generator 14 to enable the called subscriber to establish communication 20 on the channel terminated by the seized calling unit, the selection being determined by the pair of *d'u'* pulses transmitted through the identification junction.

25 The automatic exchange shown in Figure 1 will now be described in more detail with reference to Figures 2 to 17. Throughout Figures 2 to 17 all relays and automatic switches are shown in conventional manner the operating windings thereof being referenced with a letter over a figure, the figure indicating the number of relay contacts or banks of switch contacts associated with the winding. The contacts or banks of contacts associated with a winding are given the same letter reference followed by figure, references to different contacts or banks of contacts containing different figures. A contact may also have the same reference letter as its operating winding followed by a further letter or letters. All relays and switches are shown in their unoperated positions.

30 Referring to Figure 2 this is a circuit diagram of apparatus suitable for use as the sub's line circuits 12 and 13 of Figure 1. The subscriber's line is connected to line terminals LT₁ and LT₂, LT₁ being normally connected to earth through relay contacts K1 and LT₂ being normally connected through relay contacts K2, relay winding L and battery BAT₁ to earth. A uniselector having six banks of contacts S1 to S6 is operated by a winding 35 S and interruptor Sdm. The automatic interruptor operation may be as described on page 226 of *Telephony*, volume 2 by J. Atkinson, published by Sir Isaac Pitman & Sons, Ltd. 1950. This work by Atkinson will be hereinafter referred to as *Telephony* (either vol. I or II) by 40 Atkinson. Each of the banks S1, S2 and S3 has 25 fixed contacts, a first of the contacts being the "home" contact, the next 12 being "out" contacts, and the other 12 being "in" contacts.

45 The banks S1 and S2 are for carrying speech, the wipers thereof being connected to LT₁ and LT₂ respectively, when the apparatus is in use, by relay contacts K1 and K2. Contacts 2 to 13 of S1 are connected to 12 output terminals respectively of which one is shown at +O₁, and contacts 14 to 25 are connected to 12 input terminals respectively of which one is shown at +I₁. Contacts 2 to 13 of S2 are connected to 12 output terminals of which one is shown at -O₁, and contacts 14 to 25 are connected to 12 input terminals of which one is shown at -I₁. The bank S3 is used for control purposes, contacts 2 to 13 being connected to 12 output terminals respectively of which one is shown at PO₁, and contacts 14 to 25 being connected to 12 input terminals of which one is shown at PI₁.

50 Bank S4 has an insulated home contact and a homing arc BC₁. The function of the homing arc is as described

on pages 259 and 260 of Telephony, vol. II by Atkinson.

Bank S5 has an insulated home contact, an arcuate contact BC₂ extending over the equivalent of contacts 2 to 13 on S1, S2 and S3, and a further arcuate contact BC₃ extending over the equivalent of contacts 14 to 25 on S1, S2 and S3. Contact BC₂ is connected through relay contacts Z2 to earth.

Bank S6 has an insulated home contact, an arcuate contact BC₄ extending over the equivalent of contacts 2 to 13 of S1, S2 and S3, and a further arcuate contact BC₅ extending over the equivalent of contacts 14 to 25 on S1, S2 and S3. Contact BC₅ is connected to an output terminal CS1.

The home contact on S3 is connected through relay contacts L1 to earth. The wiper of S3 is connected through contacts K3 and L1 to earth through contacts L2, and K4 to contacts Sdm; and through a rectifier W₁ 15 and meter winding M to earth.

The wiper of S4 is connected through contacts L2 to contacts K4 and to the wiper of S5.

The wiper of S6 is connected through relay contacts to the moving contact of contacts K6 which is connected through a rectifier WX2 to a terminal RT, and through a resistor R₂₈₂ to a terminal RTX. The fixed contact of relay contacts K6 is connected to an output terminal BJI. The terminal RT is also connected through resistor R₁, a rectifier WX1, and a resistor R₂ in series to the control grid of a gas-filled triode valve V₁ the control grid being connected to earth through a capacitor CX₁. An input terminal SX1464 is connected through a rectifier W₂ to the junction of the resistor R₁ and rectifier WX1. The cathode lead of the valve V₁ has in series therewith a relay winding Z and the anode of the valve V₁ is connected through relay contacts K5 to the terminal HT+1 of a source (not shown) of D. C. whose negative terminal is earthed. A relay winding K is connected between contacts Sdm and L1.

Referring now to Figure 3 this is a circuit diagram of apparatus suitable for use as the calling unit 15 of Figure 1. It will be assumed that this calling unit is that connected to terminals +O₁, -O₁ and PO₁ of Figure 2, these terminals also being shown in Figure 3. Terminal +O₁ is connected through relay contacts D1 and one winding of relay A to earth. Terminal -O₁ is connected through relay contacts D2, a second winding of relay A and a battery BAT₃ to earth. Terminals +O₁ and -O₁ are also connected through capacitors C₁ and C₂ respectively to a winding MW₁ of a hybrid transformer HY₁ which has a balancing resistor RB. The function of the hybrid transformer and balancing resistor is as described on page 83, vol. I of Telephony by Atkinson.

The winding OW₁ of the hybrid transformer is connected through a capacitor C₃ to the control grid of a pentode valve V₄ whose anode is connected through a load resistor R₃ to the positive terminal of a source HT+2 of D. C. whose negative terminal is earthed. The cathode of the valve V₄ is earthed, the screen grid is connected directly to the source HT+2, and the suppressor grid is connected through a resistor R₄ to the negative terminal of a bias source -GB₁ whose positive terminal is earthed. The suppressor grid is also connected through a capacitor C₄ and relay contacts B₅ to a terminal GP. The anode of the valve V₄ is connected through a capacitor C₅ to a terminal GSP₁.

Winding IW₁ of the hybrid transformer HY₁ is connected to the output of a low-pass filter FIL₁. One input terminal of the filter is connected to the anode of a pentode valve V₃ and the other to earth through a capacitor C₆ and through a resistor R₅ to the positive terminal of a source HT+3 of D. C. The suppressor grid and cathode of the valve V₃ are connected to earth.

A terminal RSPO₁ is connected through a capacitor C₈ to the control grid of a pentode valve V₅ whose cathode is earthed. Negative bias is applied to the control grid

of the valve V₅ from the negative terminal of a bias source -GB₂₀ whose positive terminal is earthed. The anode of the valve V₅ is connected through the primary winding of a transformer XF₁ to the positive terminal of a source HT+4 of D. C. whose negative terminal is earthed. The screen grid of the valve V₅ is connected directly to the source HT+4 and the suppressor grid is connected through a resistor R₆ to the negative terminal of a bias source -GB₃ whose positive terminal is earthed. The suppressor grid of the valve V₅ is also connected through a capacitor C₉ and the contacts B₅ to the terminal GP.

The transformer XF₁ has two secondary windings S₁XF₁ and S₂XF₁. One terminal of winding S₁XF₁ is connected to the negative terminal of a bias source -GB₂ and the other terminal is connected through a rectifier W₅, and a resistor R₇ to the control grid of the pentode valve V₃ and is connected through a rectifier W₃ to the negative terminal of a bias source -GB₄ whose positive terminal is earthed. One terminal of the winding S₂XF₁ is connected to the negative terminal of the source -GB₄ and the other terminal of the winding S₂XF₁ is connected through a rectifier W₆ to the control grid of the valve V₃. The negative terminal of the source -GB₄ is also connected to the control grid of V₃ through a rectifier W₄ and a capacitor C₁₀ is connected between the control grid of V₃ and earth.

A terminal ASPO₁ is connected through a rectifier W₇ and capacitor C₁₁ to the control grid of a triode valve V₆ whose cathode is earthed and whose anode is connected through a relay winding D to the positive terminal of a D. C. source HT+5 whose negative terminal is earthed. The control grid of the valve V₆ is also connected through a rectifier W₈ to the negative terminal of a bias source -GB₅ whose positive terminal is earthed. The junction of the capacitor C₁₁ and the rectifier W₇ is connected to the terminal GP through a resistor R₈.

A relay winding J has one terminal connected to earth through a battery BAT₄. The other terminal of the relay winding J is connected to earth through relay contacts D₃, a busbar BUS₁ and relay contacts B₄. The busbar is connected through relay contacts E₁, one winding of relay E and a battery BAT₅ to earth. A control terminal P₁ is connected either directly to earth or through the other winding of relay E and a battery BAT₆ to earth depending upon the setting of relay contacts B₃ and E₃. The busbar BUS₁ is connected through relay contacts G₁, one winding of a relay G and a battery BAT₇ to earth. The other winding of the relay G has one terminal connected to earth through a battery BAT₈, and has its other terminal connected directly to a terminal BU₁. The busbar is also connected through relay contacts E₂ to an output terminal AL.

Terminal HO is connected through relay contacts D₅, E₄ and A₁ to earth. A relay winding B has one terminal connected through contacts A₁ to earth and the other through a battery BAT₉ to earth. An output terminal IMP is connected through relay contacts B₂ and A₁ to earth.

Input terminals Td' and Tu' are connected together through resistors R₉ and R₁₀ and the junction of these two resistors is connected through relay contacts E₆ to an output terminal Rd'u'.

Terminal PO₁ is connected through relay contacts B₁ to relay contacts D₄ which depending upon their setting, provide either an earth connection or a connection to relay contacts J₁. The relay contacts J₁ provide either an earth connection or a connection through a resistor R₁₁ and a battery BAT₁₀ to earth.

The cathode of a gas-filled triode valve V₂ is connected to earth through relay contacts A₂ and its anode is connected through a relay winding F to the positive terminal of a suitable source HT+6 of D. C. whose negative terminal is earthed. A capacitor C₁₂ is normally connected to the positive terminal of a source HT+7 of D. C. whose

negative terminal is earthed. The control grid of the valve V_2 is connected to the capacitor C_{12} through a resistor R_{12} and the contacts $E5$.

A source (not shown) of busy tone is connected to the terminal BT which is connected to the centre winding of the relay A through relay contacts G_2 .

A source (not shown) of dialling tone is connected to the terminal DT which is connected through relay contacts $F1$ to the centre winding of the relay A .

Referring now to Fig. 4 this is a circuit diagram of an allotter suitable for use at 24 in Fig. 1. The terminal AL corresponds to the terminal AL of Fig. 3, and is connected through a relay winding ST and a battery BAT_{11} to earth. A uni-selector FD has four banks of contacts $FD1$, $FD2$, $FD3$, and $FD4$ whose wipers are controlled by automatic stopping apparatus including winding FD and contacts $FDdm$. The wiper of the bank $FD1$ is connected through relay contacts $ST1$, the contacts $FDdm$, the winding FD and a battery BAT_{12} to earth. The junction of the contacts $FDdm$ and the winding FD is connected to earth through relay contacts $FK2$ and $DR4$. The fixed contacts of the bank $FD1$ are connected to output terminals respectively of which one is shown at Q . A terminal R is connected through a relay winding DK and relay contacts $ST2$ to the moving contact of the bank $FD1$. The terminal R is also connected through contacts $ST3$, and $DK1$ to contacts $ST1$. The contacts $DK1$ are also connected through relay winding DR and a battery BAT_{13} to earth.

The bank contacts of the bank $FD4$ are connected to output terminals respectively of which one is shown at X . The wiper of the bank $FD4$ is connected through relay contacts $DR3$, $FK1$, and $DR1$ to earth.

The fixed contacts of the bank $FD3$ are connected to output terminals respectively of which one is shown at P_2 . The wiper of the bank $FD3$ is connected through relay contacts $DR2$ and one winding of relay FK to earth. One terminal of the other winding of the relay FK is connected through the contacts $FK1$ and $DR1$ to earth, and the other terminal thereof is connected through a battery BAT_{14} to earth.

The bank contacts of the bank $FD2$ are connected to output terminals respectively of which one is shown at Y . The wiper of $FD2$ is connected through the contacts $FK1$ and $DR1$ to earth.

Referring now to Fig. 5, this is a theoretical circuit diagram of a suitable register and calling unit finder for use in the arrangement of Fig. 1. The terminals IMP , $Rd'u'$, BU_1 , HO , and P_1 correspond to the terminals of the same reference in Fig. 3, and terminals Y , P_2 , X , R and Q correspond to those of the same reference in Fig. 4.

The calling unit finder section of the arrangement shown in Fig. 5 comprises a uni-selector CUF having six banks $CUF1$ to $CUF6$, whose wipers are driven by an automatic stepping circuit including a battery BAT_{15} connected between earth and one terminal of winding CUF , and contacts $CUFdm$ connected between the other terminal of the winding CUF and the terminal Y . The IMP terminals of several callings units (15, Fig. 1) are connected to the bank contacts respectively of the bank $CUF1$ whose wiper is connected through relay contacts $H1$, a relay winding AA and a battery BAT_{16} to earth. The terminals $Rd'u'$ of the several calling units are connected to the bank contacts of $CUF2$ respectively whose wiper is connected through a resistor R_{205} and a rectifier $WX14$ to an output terminal RO . The BU_1 terminals of the several calling units are connected to the bank contacts respectively of $CUF3$ whose wiper is connected through relay contacts $BR1$ to earth. The HO terminals of the several calling units are connected to the bank contacts respectively of $CUF4$ whose wiper is connected through a relay winding H and a battery BAT_{32} to earth. The P_1 terminals of the several calling units are connected to the bank contacts respectively of $CUF5$ whose wiper is connected to terminal P_2 . The bank $CUF6$ is a homing bank. Each of

the banks $CUF1$ to $CUF6$ has an insulated home contact.

The terminal P_2 is also connected through relay contacts $KF6$ to earth. The terminal R is connected through relay contacts $KF6$ to earth and through relay contacts $KF5$ to terminal Q which is also connected through contacts $K5$ and a battery BAT_{17} to earth. The terminal X is connected through a relay winding KF and battery BAT_{18} to earth, and through relay contacts $KF1$ and $H2$ to earth.

A uni-selector ZZ has two banks $ZZ1$ and $ZZ2$ whose wipers are driven by an automatic stepping circuit including winding ZZ and contacts $ZZdm$. The winding ZZ has one terminal connected through a battery BAT_{19} to earth and the other through relay contacts $BB1$ to earth, and through the contacts $ZZdm$ to the wiper of $ZZ2$. A capacitor C_{13} and resistor R_{13} are employed to reduce sparking between the contacts $ZZdm$ when in operation. The bank $ZZ2$ is a homing bank and is connected to earth through a relay contact $KF3$.

The register section of Fig. 5 comprises four uni-selectors M , C , D and U . The uni-selectors are operated by impulses caused by the operation of relay contacts $AA1$ as will be described later. The moving contact of $AA1$ is connected through relay contacts $H7$ to earth and the fixed contact of $AA1$ is connected through relay contacts PQ_1 to the wiper of the uni-selector bank $ZZ1$. The first four bank contacts of $ZZ1$ are connected to the windings M , C , D and U respectively whose other terminals are connected to earth through batteries BAT_{20} to BAT_{23} respectively. The first four bank contacts of $ZZ1$ are also connected through contacts Mdm , Cdm , Ddm and Udm to the wipers of the banks $M2$, $C2$, $D2$ and $U2$ respectively. Each of these banks is a homing bank. The homing arcs of the homing banks $M2$, $C2$, $D2$ and $U2$ are connected to earth through relay contacts $H6$, $H3$, $H4$ and $H5$ respectively.

The fifth contact of $ZZ1$ is connected through a relay winding PQ and a battery BAT_{24} to earth, and through relay contacts PQ_3 and KF^4 in series to earth. A relay winding BB is connected between the fixed contact of $AA1$ and the negative terminal of a battery BAT_{25} whose positive terminal is earthed.

Each of the banks $M1$, $C1$, $D1$ and $U1$, has an insulated home contact and ten bank contacts. The ten bank contacts of $M1$ are connected to terminals MP_1 to MP_9 and MP_0 respectively. The ten bank contacts of $C1$ are connected to terminals CP_1 to CP_9 and CP_0 respectively. The ten bank contacts of $D1$ are connected to terminals DP_1 to DP_9 and DP_0 respectively, and those of $U1$ are connected to terminals UP_1 to UP_9 and UO_0 respectively. The wipers of the banks M_1 , C_1 , D_1 , and U_1 are connected through rectifiers W_{19} , W_{11} , W_{12} , and W_{13} respectively to a busbar $BUS2$ which is connected through a resistor R_{271} to the positive terminal of a source of $D. C. HT+100$ whose negative terminal is earthed. The bus-bar $BUS2$ is also connected through a capacitor C_{100} to the control grid of a triode valve V_{100} whose anode is connected to the positive terminal of the source $HT+100$ and whose cathode is connected to earth through a cathode load resistor R_{205} . The control grid of the triode V_{100} is also connected through a resistor R_{272} to the negative terminal of a bias battery $-GB_{101}$ whose positive terminal is earthed. The cathode of the triode V_{100} is connected directly to an output terminal RO and through a rectifier $WX14$ to a second output terminal ROX . The terminal ROX is connected through a resistor R_{206} to the wiper of the uni-selector bank $CUF2$ and thence to the terminal $Rd'u'$.

An input terminal BJO is connected through a resistor R_{19} and a capacitor C_{13} and resistor R_{13} in series to the control grid of a gas-filled triode V_7 . The junction of R_{13} and C_{13} is connected through a resistor R_{14} to the positive terminal of a source $HT+8$ of $D. C.$ whose negative terminal is earthed. The cathode of the valve V_7 is connected to earth through a resistor R_{15} and the anode of the valve V_7 is connected through relay contacts $H8$

to the positive terminal of a source HT+9 of D. C. whose negative terminal is earthed.

The terminal BJO is also connected through a capacitor C₁₄ and a resistor R₁₆ to the control grid of a gas-filled triode V₈ whose cathode is earthed. The junction of C₁₄ and R₁₆ is connected through two resistors R₁₇ and R₁₈ in series to the cathode of the valve V₇, and the junction of R₁₇ and R₁₈ is connected to earth through a capacitor C₁₅. The anode of the valve V₈ is connected to the positive terminal of the source HT+9 through contacts H₈ and a relay winding BR. The junction of the resistor R₁₉ and the capacitor C₁₃ is connected through a rectifier W₁₄ to the wiper of switch bank CUF2.

Referring now to Figures 6 and 7, part of the calling junction 25 of Figure 1 is shown in Figure 6, and Figure 7 shows a further part. Assuming 20 registers to be used the pulses appearing at the output terminals RO of the 20 registers are combined in two groups of ten by means of rectifiers W₁₂₀ as shown in Figure 6. The combined pulses in the first group appear across a resistor R₂₂₇ and those in the second group across a resistor R₂₂₈.

The two groups of pulses appearing across the resistors R₂₂₇ to R₂₂₈ are applied to the control grids of two pentode valves V₁₀₃ and V₁₀₄ respectively which have a common anode load resistor R₂₃₂. A resistor R₂₃₃ and a capacitor C₁₀₄ are for decoupling purposes. The combined outputs from the valves V₁₀₃ and V₁₀₄ appearing across the common load resistor R₂₃₂ are applied through a capacitor C₁₀₅ to the control grid of a valve V₁₀₈ whose cathode is connected to earth through a self-biasing circuit comprising a resistor R₂₃₄ and a capacitor C₁₀₆. A rectifier W₁₂₁ and a resistor R₂₃₅ are connected in parallel between the control grid of the valve V₁₀₈ and earth and function to render the pulses appearing at the control grid of the valve V₁₀₈ of positive polarity.

The output of the valve V₁₀₈ appearing across a load resistor R₂₃₆ is applied through a capacitor C₁₀₇ and a resistor R₂₃₇ to the control grid of a valve V₁₀₉ which has a cathode load resistor R₂₃₈. Negative bias is applied through a resistor R₂₃₉ to the control grid of the valve V₁₀₉ from the negative terminal of a bias source —GB100 whose positive terminal is earthed. The cathode of the valve V₁₀₉ is connected through a capacitor C₁₀₈ to a terminal TX which is also connected through a resistor R₂₃₀ to the negative terminal of the source —GB100.

In Figure 7 the terminal TX is that also shown in Figure 6 and is connected through resistors P₂₄₀ to R₂₄₉ to the control grids of ten triode valves V₁₁₀ to V₁₁₉ whose cathodes are connected to earth through load resistors R₂₅₀ to R₂₅₉ respectively. The outputs appearing across the cathode load resistors of the ten valves V₁₁₀ to V₁₁₉ are applied to ten groups respectively of triode valves connected as cathode followers. Each of these groups has ten cathode followers and three of the cathode followers in the group connected to the output of the valve V₁₁₄ are shown in Figure 7.

The output voltages appearing at the cathode of the valve V₁₁₄ are applied through a capacitor C₁₀₉ and resistors R₂₆₀ to R₂₆₂ to the control grids of three triode valves V₁₂₀, V₁₂₁ and V₁₂₂ in the group shown. The cathodes of the three valves V₁₂₀ to V₁₂₂ are connected to earth through resistors R₂₆₃ to R₂₆₅ and to three output terminals RT₁, RT₂ and RT₃ respectively. Negative grid bias is applied through a resistor R₂₆₆ to the control grids of the triodes V₁₂₀ to V₁₂₂ from the negative terminals of a bias source —GB101 whose positive terminal is earthed. The anode circuits of all the valves in Figure 7 are decoupled as shown.

The identification junction 25' is identical with the calling junction 25 shown in Figs. 6 and 7 the terminals ROX of the several registers replacing the terminals RO in Fig. 6 and the output terminals RT being replaced by

output terminals RTX of which one is shown in Fig. 2.

Referring to Figure 8 this is a theoretical circuit diagram of a suitable called unit (16, Figure 1). In Figure 8 a control terminal PI₂ is connected through relay contacts RB₃, a relay winding RQ and a battery BAT₂₈ to earth. The terminal PI₂ is connected to one of the PI terminals of the bank S₃ of the uniselector in one of the sub's line circuits (Figure 2). Two terminals +I₂ and —I₂ are connected through relay contacts F₂ and F₃ respectively, and capacitors C₂₂ and C₂₃ to a winding MW₂ of a hybrid transformer HY₂. An output winding OW₂ of the transformer HY₂ has one terminal earthed and the other terminal thereof is connected through a capacitor C₂₄ to the control grid of a pentode valve V₂₄ whose cathode is earthed. The anode of the valve V₂₄ is connected through a load resistor R₃₂ to the positive terminal of a source HT+11 of D. C. whose negative terminal is earthed. The anode is also connected through a capacitor C₂₅ to an output terminal RSP₂, and the screen grid is connected directly to the positive terminal of the source HT+11. Negative bias is applied to the control grid of the valve V₂₄ from a bias source —GB₂₁. The suppressor grid is connected through a capacitor C₂₆ to relay contacts CD₁, and through a resistor R₃₃ to the negative terminal of a bias source —GB₈ whose positive terminal is earthed.

An input terminal GSPO₁ is connected through a capacitor C₂₇ to the control grid of a pentode valve V₂₅ whose cathode is earthed. The control grid of the pentode V₂₅ is also connected through a resistor R₃₄ to the negative terminal of a bias source —GB₉ whose positive terminal is earthed. The anode of the pentode V₂₅ is connected through the primary winding of a transformer XF₂ to the positive terminal of a source HT+12 of D. C. whose negative terminal is earthed. The anode is also connected through a capacitor C₂₈ to the control grid of a triode valve V₂₆ whose cathode is earthed. The anode of the triode V₂₆ is connected through a relay winding RB to the positive terminal of a source HT+13 of D. C. negative terminal is earthed. The control grid of the triode V₂₆ is connected through a rectifier W₁₅ to the negative terminal of a bias source —GB₁₁ whose positive terminal is earthed. The screen grid of the pentode V₂₅ is connected through a resistor R₃₅ to the positive terminal of the source HT+12. The suppressor grid is connected through a resistor R₃₆ to the negative terminal of a bias source —GB₁₀ whose positive terminal is earthed, and through a capacitor C₂₉ to the relay contacts CD₁.

The transformer XF₂ has two secondary windings S₁XF₂ and S₂XF₂. One terminal of the winding S₁XF₂ is connected to the negative terminal of a bias source —GB₁₂ whose positive terminal is earthed, and the other terminal thereof is connected through a rectifier W₁₆ to the control grid of a pentode valve V₂₇ whose cathode is earthed. One terminal of the winding S₂XF₂ is connected to the negative terminal of a bias source —GB₁₃ whose positive terminal is earthed, and the other terminal of the winding S₂XF₂ is connected through a rectifier W₁₇, and a resistor R₃₇ to the control grid of the pentode V₂₇.

60 A rectifier W₁₈ is connected between the negative terminal of the source —GB₁₂ and the left-hand terminal of the winding S₂XF₂ in the drawing.

The primary winding of the transformer XF₂ is tuned by a capacitor C₃₀ which is shunted by a resistor R₁₉₄.

65 The anode of the pentode V₂₇ is connected through the input circuit of a low-pass filter FIL₂ to the positive terminal of a source HT+14 of D. C. whose negative terminal is earthed. The screen grid of the pentode V₂₇ is connected through a resistor R₃₈ to the positive terminal of the source HT+14 and is decoupled by a capacitor C₃₂. One output terminal of the low-pass filter FIL₂ is connected to earth and the other output terminal is connected through the winding IW₂ of the hybrid transformer HY₂ to earth.

75 The terminal —I₂ is normally connected to earth.

through the relay contacts F3 and a battery BAT₃₃, and the terminal +I₂ is normally connected through the relay contacts F2 and through one winding of a relay F to the moving contact of relay contacts RB4. These contacts are normally open and the fixed contact thereof is connected through the secondary winding of a transformer XF₃ to earth. The primary winding of the transformer XF₃ is connected to terminals TR to which ringing current is applied from a suitable source (not shown). The contacts F2 are bridged by a capacitor C₆₄. One terminal of the other winding of relay F is connected through a battery BAT₂₉ to earth and the other terminal thereof is connected through relay contacts F1 and RB1 to earth. One winding of a relay RD is connected between the right-hand plate (in the drawing) of the capacitor C₂₂ and earth. The other winding of the relay RD has one terminal connected to the right-hand plate of the capacitor C₂₂ and has the other terminal connected through a battery BAT₃₀ to earth.

A uniselector ZRU has three banks ZRU1, ZRU2 and ZRU3, each of which has a home contact and bank contacts. The bank ZRU1 has ten bank contacts which are connected to the translator 25 to be described later. The wiper of the bank ZRU1 is connected through a resistor R₃₉ to the control grid of a gas-filled triode valve V₂₈. The cathode of the valve V₂₈ is connected to the negative terminal of a bias source GB₁₄ whose positive terminal is earthed. The anode of the valve V₂₈ is connected through relay contacts DA1 to one terminal of a relay winding DA. The other terminal of the winding DA is connected through relay contacts RQ1 and RB2 in parallel to the positive terminal of a source HT+15 of D. C. whose negative terminal is earthed.

The bank ZRU2 is a homing bank and has its homing arc BC₆ connected to earth through relay contacts DA2. The wiper of the bank ZRU2 is connected through contacts ZRU_{dm}, operating winding ZRU, a relay winding CD and a battery BAT₃₁ in series to earth. The home contact of the bank ZRU2 is connected through relay contacts RQ2 to earth.

The bank ZRU3 has ten bank contacts which are connected to ten terminals Tu₀ to Tu₉ respectively. The wiper of the bank ZRU3 is connected through a resistor R₄₀ to the fixed contact of contacts CD1.

A uniselector ZRD has three banks ZRD1, ZRD2 and ZRD3, each of which has a home contact and bank contacts. The bank ZRD1 has ten bank contacts which are connected to the translator 25. The wiper of ZRD1 is connected through a resistor R₄₁ to the control grid of a gas-filled triode V₂₉ whose cathode is connected to earth through a bias source GB₁₅. The anode of the valve V₂₉ is connected through relay contacts UA1 to one terminal of a relay winding UA and the other terminal of the winding UA is connected through the relay contacts RQ1 and RB2 to the positive terminal of the source HT+15.

The bank ZRD2 is a homing bank and the homing arc BC₇ is connected through relay contacts UA2 to earth, and the home contact through RQ2 to earth. The wiper of the bank ZRD2 is connected through the mechanically operated contact ZRD_{dm}, the operating winding ZRD, the relay winding CD and the battery BAT₃₁ in series to earth.

The bank ZRD3 has ten bank contacts which are connected to ten terminals Td₀ to Td₉ respectively. The wiper of the bank ZRD3 is connected through a rectifier W₂₀ to the fixed contact of contacts CD1.

The moving contact of the contact CD1 in addition to being connected through the capacitors C₂₆ and C₂₉ to the suppressor grids of the pentodes V₂₄ and V₂₅ respectively is connected through a resistor R₄₂ to earth and directly to the moving contact of contacts RD1. The fixed contact of contacts RD1 is connected through a resistor R₄₃ to earth and through a capacitor C₃₃ to the control grid of a triode valve V₃₁ whose cathode is earthed. Negative bias is applied through a resistor R₄₄ to the

control grid of the triode V₃₁ from the negative terminal of a bias source —GB₁₆ whose positive terminal is earthed. The anode of the valve V₃₁ is connected through a capacitor C₃₄ to an output terminal ASP₁, and through a resistor R₄₅ to the positive terminal of a source HT+16 of D. C. whose negative terminal is earthed.

The translator 25 is connected through relay contacts RQ3 to the positive terminal of a source HT+17 of D. C. whose negative terminal is earthed. Ten terminals Tu₀ to Tu₉ and ten terminals Td₀ to Td₉ are connected to the translator, and a further terminal CS₂ which is connected to the CS terminals in the sub's line circuits (see Figure 2).

Referring now to Figure 9 this is a theoretical circuit diagram of the translator 25. The translator comprises two groups of gas-filled triode valves each group containing ten valves. A first of the groups contains ten triodes V₃₂ to V₄₁ whose cathodes are connected to earth through resistors R₄₆ to R₅₅ respectively, and directly to the ten bank contacts respectively of the uniselector bank ZRU1. The anodes of the triodes V₃₂ to V₄₁ are connected together and through the relay contacts RQ3 to the terminal HT+17. The terminals Tu₀ to Tu₉ are connected through ten rectifiers W₂₁ to W₃₀ ten resistors R₆₆ to R₇₅ and ten rectifiers W₁₀₀ to W₁₀₉ respectively in series to the control grids of the triodes V₃₂ to V₄₁. The cathode of V₁₀₁ is connected through ten resistors R₈₆ to R₉₅ to the junctions of the rectifiers and resistors connecting the terminals Tu₀ to Tu₉ respectively to the control grids of the triodes V₃₂ to V₄₁. The control grids of the triodes V₃₂ to V₄₁ are connected through capacitors C₁₀₃ to C₁₁₂ and resistors R₂₀₇ to R₂₁₆ respectively to earth.

The second group contains ten triodes V₄₂ to V₅₁ whose cathodes are earthed through resistors R₅₆ to R₆₅ respectively. The cathodes of these valves are also connected directly to the ten bank contacts respectively of the uniselector bank ZRD1. The anodes of the valves V₄₂ to V₅₁ are connected together and through the relay contacts RQ3 to the positive terminal of the source HT+17. The terminals Td₀ to Td₉ are connected through ten rectifiers W₃₁ to W₄₀, ten resistors R₇₆ to R₈₅ and ten rectifiers W₁₁₀ to W₁₁₉ respectively in series to the control grids of the valves V₄₂ to V₅₁. The terminal CS₂ is connected through a capacitor C₁₀₁ to the control grid of a valve V₁₀₁ which has a cathode load resistor R₂₀₃. The cathode of V₁₀₁ is connected through ten resistors R₆₆ to R₁₀₅ to the junctions of the rectifiers W₃₁ to W₄₀ and resistors R₇₆ to R₈₅ respectively.

Referring now to Figure 10 this is a circuit diagram of an arrangement suitable for use as the GO speech junctions 17 of Figure 1. The output terminals GSP₁ to GSP₁₀₀ of the 100 calling units respectively (see GSP₁ of Figure 3) are connected to input terminals GSP₁ to GSP₁₀₀ of the arrangement of Figure 10. In Figure 10 only 10 of the terminals GSP₁ to GSP₁₀₀ are shown. The input terminals GSP₁ to GSP₁₀₀ are grouped into ten groups of ten terminals each and the ten groups are connected to the control grids of ten pentodes of which five are shown at V₅₂ to V₅₆. The terminals GSP₁ to GSP₁₀ are connected through rectifiers W₄₁ to W₅₀ respectively to the control grid of the pentode V₅₂. The other nine groups of input terminals are connected in a like manner to the control grids of the other nine input pentodes respectively. The five pentodes V₅₂ to V₅₆ have a common cathode resistor R₁₀₅, and the cathodes of the other five input pentodes (not shown) are likewise provided with a common cathode resistor. The anodes of the five input pentodes V₅₂ to V₅₆ are connected together as shown and have a common wide band anode load comprising a resistor R₁₀₇, an inductor L₁ and a capacitor C₃₅. A resistor R₁₀₇ and a capacitor C₃₆ are for decoupling purposes. The anode connections of the other five input pentodes are the same as those shown for the pentodes V₅₂ to V₅₆.

The common anode connection of the five pentodes

V_{52} to V_{56} is connected through a capacitor C_{39} to the control grid of a pentode valve V_{57} . The common anode connection of the other five input pentodes (not shown) is connected through a capacitor C_{47} to the control grid of a pentode valve V_{58} . The control grid of the pentode V_{57} is connected to earth through a rectifier W_{51} and a resistor R_{108} in parallel, and the control grid of the pentode V_{58} is connected to earth through a rectifier W_{52} and a resistor R_{111} in parallel. The screen grids of the two pentodes V_{57} and V_{58} are connected together and through a resistor R_{110} to the common cathode connection of the two pentodes V_{57} and V_{58} . The suppressor grids of these two pentodes are earthed.

The anodes of the two pentodes V_{57} and V_{58} are connected together and have a common wide band load comprising a resistor R_{112} , an inductor L_2 and a capacitor C_{37} . A resistor R_{113} and a capacitor C_{38} are for decoupling purposes, and the junction of R_{113} and C_{38} is connected to the screen grids of the two pentodes V_{57} and V_{58} .

The anodes of the two pentodes V_{57} and V_{58} are connected through a capacitor C_{40} to the control grid of a pentode valve V_{59} . The control grid of this valve is also connected to earth through a rectifier W_{53} and a resistor R_{114} in parallel. The cathode of the pentode valve V_{59} is connected to earth through a resistor R_{115} and the anode has a wide band load comprising a resistor R_{116} , an inductor L_3 and a capacitor C_{41} . A resistor R_{117} and a capacitor C_{42} are for decoupling purposes. The junction of R_{117} and C_{42} is connected to the screen grid of the valve V_{59} and the suppressor grid of the valve V_{59} is earthed.

The anode of the valve V_{59} is connected through a capacitor C_{43} to the control grid of a triode valve V_{60} , the control grid also being connected to earth through a resistor R_{118} and in parallel therewith a rectifier W_{54} and bias source GB_{17} connected in series. The valve V_{60} has a cathode load resistor R_{119} and the anode thereof is decoupled by means of a resistor R_{120} and a capacitor C_{44} . The load resistor R_{119} is coupled by means of a wide band coupling comprising two capacitors C_{45} and C_{46} and an inductor L_4 to the control grids of three cathode follower valves V_{61} to V_{63} . The control grids of these valves are also connected to earth through a rectifier W_{55} and bias source GB_{18} . The valves V_{61} to V_{63} have cathode load resistors R_{121} to R_{123} respectively and the cathodes are connected to output terminals $GSPO_1$ to $GSPO_3$ respectively.

Although three cathode followers V_{61} to V_{63} have been shown more may be used if desired.

An arrangement as shown in Fig. 10 may also be used as the Return speech junction 18 and as the metering and release junction 19 of Fig. 1. When used as the Return speech junction the terminals GSP_1 to GSP_{100} are replaced by the terminals RSF_1 to RSF_{100} (see RSF_2 , Fig. 8), and the terminals $GSPO_1$ to $GSPO_3$ are replaced by the terminals $RSPO_1$ to $RSPO_3$ (see $RSPO_1$, Fig. 3). When the arrangement of Fig. 10 is used as the metering and release junction the terminals GSP_1 to GSP_{100} are replaced by the terminals ASP_1 to ASP_{100} (see ASP_1 , Fig. 8) and the terminals $GSPO_1$ to $GSPO_3$ are replaced by terminals $ASPO_1$ to $ASPO_3$ (see $ASPO_1$, Fig. 3).

Referring now to Fig. 11 this is a circuit diagram of part of the busy junction 20 of Fig. 1. The 2,000 input terminals to the busy junction are grouped in groups of ten and of the 200 groups one is shown at BJ_1 to BJ_{10} in the figure. These 2,000 terminals are connected to the terminals BJ in the 2,000 sub's line circuits respectively (see BJ_1 in Fig. 2).

Pulses appearing at the terminals BJ_1 to BJ_{10} are combined through resistors R_{124} to R_{143} . The combined outputs of the 200 groups are combined in further groups of ten by means of rectifiers the rectifiers of one group being shown at W_{56} to W_{65} . The outputs of these 20 groups are combined in two further groups of ten each by means of resistors and a see-saw circuit. One of

these groups of resistors is shown at R_{145} to R_{154} which are connected to the control grid of a pentode valve V_{52} connected in a see-saw circuit comprising resistors R_{155} , R_{156} and R_{157} . The see-saw circuit functions as described in the M. I. T. Radiation Laboratory Series, vol. 19, chapter 2, section 3, 27 et seq., Fig. 2.12 (a) published by the McGraw-Hill Book Company Inc. A resistor R_{179} and a capacitor C_{48} are for decoupling the anode circuit of the valve V_{52} . The cathode and suppressor grid of this valve are connected to earth, the screen grid to the junction of R_{179} and C_{48} , and negative bias for the control grid is supplied from a bias battery through resistors R_{177} and R_{158} . The gain of the see-saw circuit is made substantially unity by appropriate selection of the valves of the resistors in the circuit.

The second see-saw circuit comprises a pentode valve V_{53} connected in a circuit identical with that associated with the valve V_{52} , and comprising resistors R_{160} to R_{164} and a capacitor C_{49} .

The outputs of the two valves V_{52} and V_{53} are combined through two resistors R_{159} and R_{165} and applied to the control grid of a pentode valve V_{54} connected in a further see-saw circuit. The cathode of the pentode is earthed and the anode is coupled to the control grid by means of resistors R_{166} , R_{168} , R_{169} and R_{170} . A resistor R_{167} and a capacitor C_{50} serve to decouple the anode circuit of the valve V_{54} .

The junction of the resistors R_{168} to R_{170} is connected to the control grid of a pentode valve V_{55} which is coupled to a further pentode valve V_{56} by means of a resistor R_{171} which is common to the cathodes of both valves V_{55} and V_{56} .

The anode circuit of the valve V_{56} contains an anode load resistor R_{172} and is decoupled by means of a resistor R_{173} and capacitor C_{54} . The suppressor grids of the valves V_{55} and V_{56} are earthed and their screen grids are connected to the junction of R_{173} with C_{54} .

A capacitor C_{51} serves to connect the anode of the valve V_{56} to the control grid of a triode V_{58} . D. C. restoration of the voltages applied to the control grid of the valve V_{58} is effected by a diode valve V_{57} and a resistor R_{174} . The triode V_{58} has a cathode load R_{175} and acts as a cathode follower the cathode being connected to an output terminal BJO . This terminal is connected to the terminal of like reference in each register (see Fig. 5).

A suitable high frequency pulse generator (14 of Fig. 1) will now be described with reference to Fig. 12 (a) to (e). In Fig. 12 (a) the output of an oscillator OS_1 is applied to a ringing circuit comprising a pentode valve V_{59} whose anode circuit includes the primary winding of a transformer XF_4 . The secondary winding of the transformer XF_4 has a centre tap connected to earth through a resistor R_{181} which is decoupled by a capacitor C_{54} . The lower end of the secondary winding is connected to the cathode of a diode valve V_{60} whose anode is connected through a resistor R_{182} to the positive terminal of a source $HT+18$ of D. C. whose negative terminal is earthed. The anode of the diode V_{60} is also connected directly to the control grid of a pentode valve V_{61} whose cathode is connected to earth through a bias resistor R_{183} which is decoupled by a capacitor C_{55} .

During the positive half cycles of the voltage at the cathode of the diode V_{60} this diode is non-conducting. Thus the control grid of the valve V_{61} becomes highly positive and anode current of high value flows in the anode circuit of the valve V_{61} .

During negative half-cycles of the voltage at the cathode of the diode V_{60} this diode conducts and it is arranged that the voltage at the control grid of the valve V_{61} falls below the value for anode current cut-off in the valve V_{61} . Thus the wave form of the voltage at the anode of the valve V_{61} is substantially rectangular. The "mark-to-space ratio" of this wave form can be varied by

changing the values of R_{181} and R_{183} . A value of 4:1 is used.

The potential variations at the anode of the valve V_{61} are applied through a cathode follower valve V_{62} to a terminal TA.

A diode valve V_{63} and two pentode valves V_{64} and V_{65} function in like manner to provide rectangular pulses of the same frequency but in anti-phase at a terminal TB.

The output of the valve V_{65} is differentiated by a capacitor C_{57} and resistor R_{187} then applied through an inverter comprising a valve V_{66} to a terminal TC.

In Fig. 12(b) the input terminal TC which corresponds to the terminal TC in Fig. 12(a) is coupled through two diode valves V_{67} and V_{68} to a multivibrator comprising two valves V_{69} and V_{70} . The multivibrator functions in known manner as a frequency divider and provides a division ratio of 5:1. The output voltage of this multivibrator is fed through a cathode follower valve V_{71} to an output terminal TD. The output applied to TD is also differentiated by a capacitor C_{58} and resistor R_{188} and applied to a phase inverter comprising a pentode valve V_{72} .

The output of this phase inverter is fed through two diodes V_{73} and V_{74} to a multivibrator comprising two pentodes V_{75} and V_{76} . This multi-vibrator functions as a frequency divider and provides a division ratio of 2:1, and its output is applied through a phase splitter comprising a valve V'_{73} to two terminals TE and TF. The voltage applied to the terminal TF is also differentiated by a capacitor C_{59} and resistor R_{189} and applied through a phase inverter comprising a valve V'_{74} , to a terminal TG.

In Fig. 12(c) the terminal TG, which corresponds to the terminal TG of Fig. 12(b) is connected to a further multivibrator MV₁ which functions as a frequency divider and provides a division ratio of 5:1. The output of MV₁ is applied through a cathode follower CF₁ to a terminal TH.

In Fig. 12(d) the terminal TD corresponds to the terminal TD of Fig. 12(b) and is connected to the input of a delay network DL₁ of known kind which has ten equally spaced taps T₁ to T₁₀ respectively and is terminated by a matched termination R₁₈₄. The delay of the network DL₁ is made equal to the recurrence period of the pulses applied at the terminal TD from the valve V₇₁ of Fig. 12(b), and the delay from the input to the first tap T₁ is made equal to the delay between adjacent taps.

The terminal TH in Fig. 12(d) corresponds to the terminal TH of Fig. 12(c) and is connected to the input end of a delay network DL₂ which has ten equally spaced taps T₁₁ to T₂₀. The delay of the network is made equal to the recurrence period of the pulses applied at TH and the delay from the input to the tap T₁₁ is made equal to the delay between adjacent taps. The network DL₂ is terminated by a matched termination R₁₈₅.

The pulse generator is provided with twenty output circuits of which one is shown in Fig. 12(e). In Fig. 12(e) an input terminal T₁ which corresponds to T₁ in Fig. 12(d) is connected to the control grid of a pentode V'₇₄. An input terminal TA which corresponds to TA in Fig. 12(a) is connected to the suppressor grid of the pentode V'₇₄. A cathode bias resistor R₁₈₆ decoupled by a capacitor C₅₆ provides bias for the pentode and by means of a diode V''₇₅ the suppressor grid is kept normally at negative potential as a result of the D. C. restoration action of the diode in response to the positive-going pulses applied at the terminal TA. This negative potential on the suppressor grid is arranged to be sufficient to render the pentode V''₇₄ normally non-conducting.

Thus the pentode V''₇₄ acts as a gate and a pulse applied to the terminal T₁ passes through the gate only if a pulse is simultaneously applied to the terminal TA.

The output of the valve V''₇₄ is applied through a phase inverter V''₇₆ and a cathode follower V₇₇ to an output terminal T₁₀.

The other 19 output circuits are identical with that

shown in Fig. 12(e) and their outputs appear at terminals T₁ to T₉ respectively.

The terminal TA is also connected to the suppressor grids of the gates in the four output circuits connected to the terminals T₁₂, T₁₄, T₁₆ and T₁₈ and the terminals T₃, T₅, T₇ and T₉ are connected to the control grids of those four gates.

The terminal TB of Fig. 12(a) is connected to the suppressor grids of the gates in the five output circuits connected to the terminals T₁, T₃, T₅, T₇ and T₉ and the terminals T₂, T₄, T₆, T₈ and T₁₀ are connected to their control grids.

The terminal TE is connected to the suppressor grids of the gates of the five output circuits connected to the terminals T₁₀, T₁₂, T₁₄, T₁₆ and T₁₈ and the terminals T₁₁, T₁₃, T₁₅, T₁₇ and T₁₉ are connected to the control grids thereof respectively.

The terminal TF of Fig. 12(b) is connected to the suppressor grids of the gates in the remaining five output circuits and the terminals T₁₂, T₁₄, T₁₈, T₁₉, and T₂₀ of Figure 12(d) are connected to the control grids thereof respectively.

Thus the pulses appearing at the terminals T_{d0} to T_{d9} are as shown at d₀ to d₉ in Figure 13, and the pulses appearing at the terminals T_{u0} to T_{u9} are as shown at u₀ to u₉ in Figure 13.

The pulses d₀ to d₉ and u₀ to u₉ are combined in gates (of which two will be described later) to provide the 100 communication channels. For example the pulses d₃ are applied to open and close a gate to which the pulses u₄ are applied to provide channel No. 34. Only one of the u₄ pulses passes through this gate during each d₃ pulse as will be seen from an examination of Figure 13. 100 u pulses occur during each cycle of a d pulse and the 100 u pulses are gated by the d pulses to provide the 100 channels.

The pulse width of the u pulses, and hence the channel pulses, is arranged to be about 0.5 μ sec. and the recurrence frequency of the pulses in each channel is arranged to be about 8,000 per second.

Referring to Figure 14 this is a diagram of a suitable pulse generator for use at 21 in Figure 1. The generator shown comprises an oscillator OSC₂ which generates sine waves at a frequency of 200 kc/s. The output of the oscillator OSC₂ is converted into an oscillation of square wave form by a known circuit including a valve V₁₂₃ and the oscillations of square wave form are differentiated by a circuit comprising a capacitor C₁₁₀ and a resistor R₂₈₇. The narrow pulses resulting from the differentiation are applied to the control grid of a valve V₁₂₄ connected as a cathode follower and the positive-going pulses appearing at the cathode of the valve V₁₂₄ at a frequency of 200,000 P. P. S. are passed to a terminal DT₁.

A first connection is made from the terminal DT₁ to a monostable multi-vibrator MV₁₀₀ which is arranged in known manner to function as a frequency divider providing a division ratio of 4:1. The output of the multi-vibrator MV₁₀₀ is passed to a second mono-stable multi-vibrator MV₁₀₁ which also acts as a frequency divider and provides a division ratio of 5:1. The output pulses from the multi-vibrator MV₁₀₁ which are of a frequency of 10,000 P. P. S. are passed to a terminal DT₂.

A second connection is made from the terminal DT₁ to a system of twenty bistable multi-vibrators of which four are shown at MV₁₀₂, MV₁₀₃, MV₁₀₄, and MV₁₀₅ respectively. The terminal DT₂ is also connected to the system of multi-vibrators MV₁₀₂ to MV₁₀₅.

The pulses appearing at the terminal DT₂ are arranged to "switch on" the first multi-vibrator MV₁₀₂ in the system of twenty. After 5 micro-seconds however a pulse is applied from the terminal DT₁, which switches off the multi-vibrator MV₁₀₂. The coupling between the multi-vibrators MV₁₀₂ and MV₁₀₃ is made in accordance with known technique such that when the multi-vibrator MV₁₀₂ is switched off the multi-vibrator MV₁₀₃ is switched on. This process continues until all twenty of the multi-

vibrators have been switched on and off in turn each one remaining switched on for a period of 5 micro-seconds.

Just as the last multi-vibrator is switched off the next pulse appears at the terminal DT₂ and the whole process is repeated. The twenty output terminals TD₀ to TU₉ are connected to the twenty bistable multi-vibrators respectively.

Referring to Figure 15, this is a block schematic diagram of a suitable pulse generator for use at 26 in Figure 1. The terminal DT₂ is the terminal DT₂ in Figure 14 at which pulses having a recurrence frequency of 10,000 P. P. S. appear, and is connected through two cascaded multi-vibrators MV₁₀₆ and MV₁₀₇ to a terminal DT₃. The multi-vibrators MV₁₀₆ and MV₁₀₇ are arranged to function as frequency dividers providing division ratios of 2:1 and 5:1 respectively whereby an overall division ratio of 10:1 is obtained. Thus the pulses appearing at the terminal DT₃ occur at 1,000 P. P. S. These pulses are fed into a system of ten bi-stable multi-vibrators of which four are shown at MV₁₀₈ to MV₁₁₁. The pulses appearing at the terminal DT₂ are also applied direct to the multi-vibrators MV₁₀₈ to MV₁₁₁. It is arranged, as in Figure 14, that a pulse applied to the multi-vibrator MV₁₀₈ switches it on and the next succeeding pulse from the terminal DT₂ direct switches off the multi-vibrator MV₁₀₈. The multi-vibrator MV₁₀₈ on being switched off switches on the multi-vibrator MV₁₀₉ which is switched off by the next succeeding pulse applied direct from the terminal DT₂. This process is repeated until all ten multi-vibrators in the row have been switched on and off in turn. Thus each of the multi-vibrators is switched on for 100 micro-seconds at a recurrence frequency of 1,000 per second. The output pulses from the ten multi-vibrators are applied to ten output terminals UP₁ to UP₉ and UP₀ respectively which correspond to the terminals 35 of like reference in Figure 5.

The pulses appearing at the terminal DT₃ at the frequency of 1,000 P. P. S. are passed through two further cascaded multi-vibrators MV₁₁₂ and MV₁₁₃ to a terminal DT₄. The multi-vibrators MV₁₁₂ and MV₁₁₃ provide 40 division ratios of 2:1 and 5:1 respectively and hence an overall division ratio of 10:1. Thus the pulses appearing at the terminal DT₄ have a recurrence frequency of 100 P. P. S.

These pulses are applied to a further system of ten multi-vibrators of which four are shown at MV₁₁₄ to MV₁₁₇. These function in the same manner as the multi-vibrators MV₁₀₈ to MV₁₁₁ and provide ten trains of output pulses at the terminals DP₁ to DP₉ and DP₀ respectively which correspond to the terminals of like reference in Figure 5. The duration of each of these pulses is one millisecond and the pulses in each train occur at a recurrence frequency of 100 P. P. S.

The pulses appearing at the terminal DT₄ are also applied through two cascaded multi-vibrators MV₁₁₈ and MV₁₁₉ to a terminal DT₅. The multi-vibrators MV₁₁₈ and MV₁₁₉ provide a collective division ratio of 10:1 and hence the pulses at the terminal DT₅ recur at 10 P. P. S. These are applied to another system of ten bi-stable multi-vibrators of which four are shown at MV₁₂₀ to MV₁₂₃. This system functions in the same manner as those already described to provide ten trains of output pulses at the ten output terminals CP₁ to CP₉ and CP₀ respectively. The pulses in each of these trains recur at 10 P. P. S. and have a duration of ten milliseconds each.

The pulses appearing at the terminal DT₅ are applied through two cascaded multi-vibrators MV₁₂₄ and MV₁₂₅ to a final system of ten bi-stable multi-vibrators of which four are shown at MV₁₂₆ to MV₁₂₉. The multi-vibrators MV₁₂₄ and MV₁₂₅ provide a collective division ratio of 10:1 and the final system of multi-vibrators functions in a like manner to those already described to provide ten trains of output pulses at the terminals MP₁ to MP₉ and MP₀ respectively. The pulses in these ten trains recur 75

at one P. P. S. and each pulse has a duration of 100 milliseconds.

Referring to Figure 16 this shows one of the pulses M₁ which occurs at the output terminal MP₁ of Figure 5. During each M₁ pulse ten C pulses (C₁ to C₉ and C₀) occur at the terminals CP₁ to CP₉ and CP₀ (Figure 15) respectively. Two of these C pulses are shown at C₁ and C₂. During each C pulse ten D pulses (D₁ to D₉ and D₀) occur at the terminals DP₁ to DP₉ and DP₀ respectively (Figure 15). Three trains D₁, D₂ and D₃ of the D pulses are shown. During each D pulse ten U pulses (U₁ to U₉ and U₀) occur at the terminals UP₁ to UP₉ and UP₀ respectively (Figure 15). One train of U₁ pulses is shown in Figure 16.

In addition to what is shown in Figure 15 the pulse generator 26 comprises 2,000 gate circuits (one per subscriber) of which one is shown in Figure 17. The function of these circuits is to provide a recurring sequence of 2,000 gating pulses each of 100 micro-seconds duration, the sequence recurring at the rate of once per second, and the several pulses in each sequence being applied to the 2,000 sub's line circuits respectively.

The circuit shown in Figure 17 is for providing the gating pulses for the sub's line circuit number 1464. The terminal MP₁ of Figure 15 is connected through a rectifier W₁₂₂ and a resistor R₂₆₈ to the anode of a rectifier W₁₂₃ whose cathode is connected to the terminal CP₄ of Figure 15. The anode of the rectifier W₁₂₃ is connected through a resistor R₂₆₉ to the anode of a rectifier W₁₂₄ whose cathode is connected to the terminal DP₆ of Figure 15. The anode of the rectifier W₁₂₄ is connected through a resistor R₂₇₀ to the anode of a rectifier W₁₂₅ and to an output terminal SX1464.

In operation the M₁ pulses pass through the rectifier W₁₂₂ and resistor R₂₆₈ to the rectifier W₁₂₃ which is normally conducting and provides a low impedance path whereby the M₁ pulses are dropped across the resistor R₂₆₈. Whenever a C₄ pulse occurs at the terminal CP₄ however the rectifier W₁₂₃ is rendered insulating and hence that part of each M₁ pulse which occurs during a C₄ pulse passes through the resistor R₂₆₉ to the rectifier W₁₂₄. This rectifier is normally conducting and provides a low impedance path except during the occurrence of D₆ pulses applied from the terminal DP₆. Thus only that part of each M₁ pulse which occurs during both a D₆ and C₄ pulse passes through the resistor R₂₇₀ to the rectifier W₁₂₅. This is rendered non-conducting only during the U₄ pulses applied to the terminal UP₄ and hence the only part of each M₁ pulse, in this example, to pass to the output terminal SX1464 is the part which occurs during a U₄ pulse, a D₆ pulse and a C₄ pulse.

Operation

It will be assumed that the subscriber at the station 10 of Figure 1 is calling the subscriber at the station 11 and that the number of the station 11 is 1464.

When the subscriber at the station 10 lifts his telephone handset from its rest a connection is automatically made from the terminal LT₁ of Figure 2 through the subscriber's line and telephone set back to the terminal LT₂. Thus a circuit is completed from earth through the battery BAT₁ and the relay winding L back to earth. The relay therefore operates and its contacts L₁ and L₂ close.

These contacts complete the automatic stepping circuit for the uniselector S, this circuit being from earth through the battery BAT₂, the winding S, mechanically operated contacts Sdm, the relay contacts K₄, the relay contacts L₂, the wiper and home contact of the bank S₃ and the contacts L₁ back to earth. The uniselector commences to hunt.

Referring now to Figure 3 (calling unit) it is arranged that when a calling unit is in use the terminal PO thereof (PO₁ in Figure 3) is earthed through contacts B₁ as will be described later. When, however, the calling

unit is free the contacts B1 are open (as will be described later) and the earth is removed from the terminal PO thereof.

Referring again to Figure 2, so long as the wiper of the bank S3 is passing over contacts connected to engaged calling units the automatic stepping circuit of the uniselector remains completed through the earthed terminals PO in those units. When, however, a contact connected to a free calling unit is reached the PO terminal thereof is not earthed and hence the automatic stepping circuit is broken and the motion of the wiper arrested.

The relay K is then energised through a circuit comprising the battery BAT₂, the winding S, the contacts Sdm, and the relay contacts L1. The resistance of the relay winding K is made sufficiently high to prevent further operation of the stepping circuit as a result of the current flowing in the circuit of the relay winding K.

Relay contacts K1 to K7 close. Contacts K1 and K2 connect the terminals LT₁ and LT₂ through to the wipers of the uniselector banks S1 and S2. Assuming the wiper of the bank S3 to be arrested on contact PO₁, the wipers of S1 and S2 connect the terminals LT₁ and LT₂ to the terminals +O₁ and -O₁ respectively.

Whilst this is occurring the circuit in the seized calling unit operates to put an earth on the terminal PO₁ as will be described later.

When the relay contacts K1 and K2 close the relay winding L becomes de-energised and the relay contacts L1 and L2 open. The relay K remains operated however because of the earth applied to the terminal PO₁ by the seized calling unit.

The operation of the remainder of the circuit of Figure 2 will be described later.

Referring now to Figure 3, assuming this to be the seized calling unit current flows from earth through the left hand winding of the relay windings A, through the relay contact D1, through the calling subscriber's line, back through the relay contacts D2, through the right-hand winding A and through the battery BAT₃ to earth. Thus the relay A operates and its contacts A1 and A2 close.

The contacts A2 apply an earth to the cathode of the gas-filled triode V₂, and hence prepare this valve for later operation.

The contacts A1 complete the circuit of the relay winding B the circuit being from earth through the battery BAT₉ through the winding B and the contacts A1 to earth. The relay contacts B1 to B5 close. The contacts B1 apply an earth to the terminal PO₁. The contacts B2 prepare a circuit for transmitting subsequent dialling impulses to the terminal IMP. The contacts B3 connect the terminal P₁ to the contacts E3 and thence through the left-hand relay winding E to the negative terminal of the battery BAT₆. The contacts B4 put an earth on the busbar BUS₁. The contacts B5 connect the terminal GP to the suppressor grids of the two valves V₄ and V₅.

It is assumed that the seized calling unit terminates channel No. 1. The high-frequency pulses d_0 and u_1 (Fig. 13) are therefore applied to the calling unit at T_{d0} and T_{u1} from the terminals of like reference in Fig. 12(c). The rectifier W₆₆ provides a low impedance path for all of each d_0 pulse applied to the terminal T_{d0} except that part thereof which occurs during a u_1 pulse.

The u_1 pulses render the rectifier non-conducting. Thus during the absence of the u_1 pulse the d_0 pulse applied to the terminal T_{d0} is dropped across the resistor R₁₇₉. During each u_1 pulse coincident with a d_0 pulse however, voltage is passed to the terminal GP.

The voltage pulses appearing at the terminal GP are arranged to be positive-going. The negative bias applied to the suppressor grids of the two pentodes V₄ and V₅ is arranged to be sufficient to render these two valves normally non-conducting. The amplitude of the voltage pulses applied to the suppressor grids of the two pentodes V₄ and V₅ from the terminal GP is arranged to be suf-

ficient to overcome the bias and to render these two valves conducting. Thus the valves V₄ and V₅ are gated in channel No. 1, and unmodulated pulses in channel No. 1 are transmitted from the anode of V₄, through the capacitor C₅ to the terminal GSP₁.

The manner in which a register is allotted to the seized calling unit will now be described. An earth is applied to the terminal AL through the contacts B4, the busbar BUS₁, and the contacts E2.

Referring now to the register and calling unit finder circuit of Figure 5, whenever a register is free an earth is put on to the terminal R through the contacts KF6, and a connection is made from earth through the battery BAT₁₇ and the contacts KF5 to the terminal Q.

Referring to the allotter circuit of Figure 4 the earth on the terminal AL from the seized calling unit completes the energising circuit of the relay ST through the battery BAT₁₁. Thus contacts ST1, ST2 and ST3 close. The automatic stepping circuit of the uniselector FD is

completed from earth through the battery BAT₁₂, the winding FD, the mechanically operated contacts FDdm, and the contacts ST1, DK1 and ST3 to the earthed terminal R of a free register. Thus the uniselector commences to hunt.

The contacts ST2 connect the relay winding DK between the earthed terminal R and the wiper of the uniselector bank FD1. When the terminal Q of the free register is reached by the wiper of the bank FD1 the energising circuit of the winding DK is completed through the contacts KF5 (Figure 5) and the battery BAT₁₇.

The contacts DK1 operate and hence break the automatic stepping circuit of the uniselector FD, and complete the energising circuit of the relay winding DR from the earthed terminal R through the contacts ST3 and DK1, the winding DR and the battery BAT₁₃, to earth. Thus the contacts DR1 to DR4 close.

The contacts DR1 complete a circuit from earth, through the contacts DR1, the contacts FK1, the bank FD2, the terminal Y, the mechanically operated contacts CUFdm (Figure 5), the operating winding CUF and the battery BAT₁₅ to earth. Thus the uniselector CUF of Figure 5 commences to hunt.

When the wiper of the bank CUF5 reaches the terminal P₁ connected to the terminal of the same reference in the seized calling unit (Figure 3) a circuit is completed from earth through the battery BAT₆ (Figure 3), the left-hand winding of the relay E, the contacts E3 and B3, the terminal P₁, the uniselector bank CUF5 (Figure 5) the terminal P₂, the uniselector bank FD3 (Figure 4) the contacts DR2 and the left-hand winding of the relay FK. Thus the relay E of Figure 3 and the relay FK of Figure 4 are energised. The contacts FK1 in Figure 4 also completed a circuit from earth through the battery BAT₁₄, the right-hand winding of relay FK, the contacts FK1 and DR1 to earth. This circuit holds the relay FK energised until released as will be described later.

In Figure 4 the contacts FK1 and FK2 close. The contacts FK1 complete a circuit from earth through the contacts DR1, FK1 and DR3, the uniselector bank FD4, the terminal X, the relay winding KF (Figure 5) and a battery BAT₁₈ to earth. Thus the relay KF of Figure 5 is energized. The opening of the contacts KF2 arrests the motion of the wipers of the uniselector CUF, the earth having already been removed from the terminal Y by the operation of the contacts FK1 of Figure 4. The contacts KF5 (Figure 5) disconnect the battery BAT₁₇ from the terminal Q. The contacts KF6 remove the earth from the terminal R and earth the terminals P₂ and P₁. The contacts KF3 remove the earth from the homing arc of the uniselector bank ZZ2, and the contacts KF4 prepare on earth for the contacts PQ3.

When the earth is removed from the terminal R (Figure 5) and the battery BAT₁₇ disconnected from the terminal Q by operation of the relay KF the relay DK of Figure 4 is released. The operation of the contacts

DK1 releases the relay DR and the contacts DR1 opening break the energising circuit of the right-hand winding of the relay FK. Referring to Figure 3, when the relay E is energised as previously described the contacts E1 are arranged to close before any other contacts of this relay. A holding circuit is then completed from earth through the contacts B4, the contacts E1, the right-hand winding of the relay E, and the battery BAT₅ to earth. Operation of the contacts E3 earths the terminals P₁ and hence releases the relay FK of Figure 4. Contacts E2 open and remove the earth from the terminal AL. The allotter is, therefore, released and the wipers thereof home to their home contacts.

Until the allotter is released the contacts FK2 and DR4 (Figure 4) serve to hold the uniselector FD.

Referring to Figure 3 the contacts E4 complete a circuit from earth through the contacts A1, E4 and D5 to the terminal HO. The terminal HO of Figure 5 is connected through the uniselector bank CUF4, through the relay winding H and the battery BAT₃₂ to earth. The relay H is therefore operated. The contacts H1 to H8 close and the contacts H2 serve to hold the relay winding KF energised, and hence to hold the register connected to the seized calling unit.

The contacts E5 (Figure 3) connect the charged capacitor C₁₂ to the control grid of the valve V₂ which, therefore, strikes and energises the relay winding F. The contacts F1 close and hence dialling tone is fed to the calling subscribers line through the windings of the relay A.

The contacts E6 connect the terminals Td'0 and Tu'1 to the terminal Rd'u'. The low frequency pulses d'0 and u'1 are applied to the terminals Td'0 and Tu'1 respectively and hence appear at the terminal Rd'u'.

When the calling subscriber dials the number he requires (1464 in this example) the dialling impulses operate the relay A and hence the contacts A1.

The relay H of Figure 5 is slow acting and hence is not affected by the rapid operation of the contacts A1 of Figure 3. The contacts H1 connect the terminal IMP through the uniselector bank CUF1, the relay winding AA and the battery BAT₁₆ to earth. Thus the operation of the contacts A1 of Figure 3 is followed by the contacts AA1 of Figure 5. The contacts H7 earth the moving contact of the contacts AA1 and hence each time the contacts AA1 are closed by a dialling impulse of the first digit a circuit is made from earth through the contacts H7, AA1 and PQ1, the wiper of the uniselector bank ZZ1, the first bank contact of ZZ1, the operating winding M and the battery BAT₂₀ to earth. Thus in the present example where the number of impulses in the first digit is one the wiper on the uniselector bank M1 is set to the first bank contact and hence is connected to the terminal MP₁.

The relay BB is slow operating and its contacts BB1 close and open only once for each digit dialled irrespective of the number of impulses in the digit the energising circuit for the winding BB being from earth through the contacts H7 and AA1, the winding BB and the battery BAT₂₅ to earth. Thus when the first digit of the wanted number is being dialled the relay contacts BB1 close and remain closed until the dialling impulses for that digit end. The contacts BB1 then open and as a result the wiper of the uniselector bank ZZ1 moves to its second contact.

The dialling impulses of the next digit (4 in this example) are therefore applied to actuate the operating winding of the uniselector C. The wiper of the bank C1 is, therefore, connected through to the terminal CP₄. Likewise the dialling impulses of the third and fourth digits dialled (6 and 4 in this example) are applied to actuate the operating windings of the uniselectors D and U respectively and hence the wipers of the banks D1 and U1 are connected through to the terminals DP₆ and UP₄ respectively.

The pulses M₁ to M₉ and M₀ generated by the low fre-

quency pulse generator 26 of Figure 1 are applied to the terminals MP₁ to MP₉ and MP₀ respectively of Figure 5. Likewise the pulses C₁ to C₉ and C₀ are applied to the terminals CP₁ to CP₉ and CP₀ respectively, the pulses D₁ to D₉ and D₀ are applied to the terminals DP₁ to DP₉ and DP₀ respectively, and the pulses U₁ to U₉ and U₀ are applied to the terminals UP₁ to UP₉ and UP₀ respectively.

Thus the pulses M₁C₄D₆ and U₄ appear at the wipers of the four uniselector banks M₁, C₁, D₁ and U₁ respectively.

The anodes of all the rectifiers W₁₀ to W₁₃ are connected to the bus-bar BUS₂ which is at positive potential, and hence these rectifiers are normally conducting and provide a low impedance path to earth. When an M₁ pulse occurs this renders the rectifier W₁₀ non-conducting but as the remaining rectifiers W₁₁ to W₁₃ are still conducting the potential of the bus-bar BUS₂ is not altered. Likewise when any C, D or U pulses occur in the absence of other pulses the potential of the bus-bar BUS₂ remains unaltered. When U, D, C and M pulses occur simultaneously however the low impedance path between the bus-bar BUS₂ and earth is removed and the potential of the bus-bar is increased.

25 In the present example the pulses appearing at the wipers of the uniselector banks M₁, C₁, D₁, and U₁ are the pulses M₁, C₄, D₆, U₄. Thus the bus-bar BUS₂ becomes positive for the duration of each U₄ pulse occurring during D₆, C₄ and M₁ pulses. The bus-bar BUS₂ remains positive for the duration of the U₄ pulse and this U₄ pulse passes through the capacitor C₁₀₀ to the control grid of the valve V₁₀₀ and hence appears at the cathode valve V₁₀₀ and the output terminal RO. The d'u' pulses applied to the resistor R₂₀₆ from the uniselector bank CUF₂ are normally dropped across the resistor R₂₀₆ because of the low impedance path provided through the rectifier WX₁₄ and the cathode resistor R₂₀₆ of the triode V₁₀₀. Whenever the U₄ pulses appears, however, at the terminal RO this pulse renders the rectifier WX₁₄ nonconducting whereby the last said low impedance path is broken for the duration of the U₄ pulse and the d'u' pulses occurring during that U₄ pulse interval pass to the output terminal ROX.

40 The 100 microsecond recurring U₄ pulse appearing at the terminal RO passes through the calling junction 25 of Figure 1 and is applied to the terminal RT in all the subscribers line circuits (Figure 2). Simultaneously with the application of the calling pulse in channel 1464 a gating pulse is applied at the terminal SX1464, in the called subscriber's line circuit and no other, and the calling pulse applied at RT passes through the resistor R₁ and the rectifier WX₁ and charges the capacitor CX₁. The voltage is held in the capacitor CX₁ and strikes the tube V₁.

45 The resulting anode current energises the relay Z and contacts Z1 and Z2 close.

50 The contacts Z1 complete the energising circuit of the relay L and hence the relay contacts L1 and L2 close. The contacts Z2 earth the contact BC₂ of the uniselector bank S₅.

55 The contacts L1 complete a circuit from earth through the home contact and wiper of the uniselector control bank S₃, through the contacts L2, K4 and Sdm, the operating winding and the battery BAT₂ to earth. The uniselector S commences to hunt. The earth on the contact BC₂ of the bank S₅ ensures that the uniselector steps over the "out" contacts on the banks S₁, S₂ and S₃ on to the "in" contacts.

60 Referring to Figure 8 (called unit) when the called unit is free the terminal PI₂ is connected through the contacts RB₃, the relay winding RQ and the battery BAT₂₅ to earth, and hence the terminal PI₂ is of negative potential. When, however, the called unit is engaged the contacts RB₃ are closed (as will be described later) whereby the terminal PI₂ is earthed.

65 Thus, referring again to Figure 2, the wiper of the

bank S3 supplies an earth for the automatic stepping circuit of the uniselector S so long as the wiper is passing over IN contacts connected to engaged called units. When a contact is reached connected to a free called unit, however, the automatic stepping circuit is broken and the motion of the wipers arrested.

The relay K then becomes energized through L1, the earth having been removed from the wiper of S3 and hence from the contacts K4. The contacts K1 and K2 connect the line terminals LT₁ and LT₂ to the seized called unit.

The contacts K3 close and connect the winding K to the wiper of the bank S3.

The contacts K4 open and hence the moving contact of the contacts K4 is disconnected from the moving contact of the contacts L2 and from the wiper of the bank S5.

The contacts K5 open and extinguish the valve V₁ whereby the relay Z becomes de-energized. The contacts Z1 open and de-energise the relay L. The contacts L1 open and remove the direct earth from the relay winding K. The relays Z and L are, however, slow-operating and it is arranged that the earth from the seized called unit is applied to hold the relay K before the contacts L1 open as will be described later. The contacts L2 prepare a homing earth from the bank S4 and the contacts Z2 open and remove the earth from the contact BC₂ of the bank S5.

The relay contacts K6 connect the junction of WX₂ and R202 to the terminal BJ₁ for a purpose to be described later, and the contacts K7 connect the junction of WX₂ and R202 through the uniselector bank S6 to the terminal CS₁.

As soon as the relay K operates, and whilst the relays Z and L are opening, the relay RQ of the seized called unit Figure 8 becomes energised, the energising circuit being from earth through the winding RQ, the contacts RB3, the uniselector bank S3 of Figure 2, the contacts K3 and L1 to earth. Thus the contacts RQ1, RQ2 and RQ3 of Figure 8 close. The contacts RQ1 apply H. T. to the two valves V₂₈ and V₂₉. The contacts RQ2 complete the automatic stepping circuits of the uniselectors ZRU and ZRD, and in addition complete the energising circuit of the relay CD. Thus the uniselectors ZRD and ZRU start the hunt, and whilst they are hunting the wipers of the banks ZRD3 and ZRU3 are isolated from the valves V₂₄, V₂₅ and V₃₁ by the opening of the contacts CD1. The relay contacts RQ₃ apply HT to the translator 25.

Referring again to Figure 2 the d'u' pulses applied to the terminals RTX are normally dropped across the resistor R₂₀₂, a low impedance path being provided through the rectifier WX₂. When, however, the calling pulses appear at the terminal RT they render the rectifier WX₂ non-conducting for the duration of each calling pulse. Thus the low impedance path is broken and the d'u' pulses appearing during each calling pulse in the channel 1464 pass through the relay contacts K7 to the wiper of the uniselector bank S₆ and pass through the arcuate contact BC₅ to the output terminal CS₁.

Referring to Figure 9 the d' and u' pulses arriving at the terminal CS₂ from the called subscriber's line circuit pass to the control grid of the valve V₁₀₁ and hence appear at the cathode of the valve V₁₀₁. From there the pulses are applied to the control grids of the valves V₃₂ to V₅₁ through the resistors R₈₈ to R₁₀₅ and pulse lengthening circuits comprising the rectifiers W₁₀₀ to W₁₁₉ and capacitors C₁₀₃ to C₁₂₂. The rectifiers W₂₁ to W₄₀ are, however, conducting to these pulses except the rectifiers to which d' and u' pulses are applied from the terminals T₁₀' to T₁₁' simultaneously with the d' and u' pulses arriving at the terminal CS₂. In this example the pulses d'₀ and u'₁ appear at the terminal CS₂ simultaneously with the pulses d'₀ and u'₁ applied at the terminals T₁₀' and T₁₁'. Thus the rectifiers W₃₁ and W₂₂ are non-conducting in this example and permit the d'₀ and u'₁ pulses applied to the terminal CS₂' to pass to the control grids

of the valves V₄₂ and V₃₃ respectively. These two valves strike and hence their cathodes become positive.

When the wiper of the bank ZRU1 reaches the bank contact connected to the cathode of the valve V₃₃ the positive potential appears at the control grid of the valve V₂₈ (Figure 8) and this valve strikes. Similarly the valve V₂₉ (Figure 8) strikes when the wiper of the bank ZRD1 reaches the bank contact connected to the cathode of the valve V₄₂.

Referring to Figure 8, when the valves V₂₈ and V₂₉ strike the relays DA and UA become energised by the anode circuits of these two valves. Thus the contacts DA1, DA2, UA1 and UA2 are operated. The contacts DA1 hold the relay DA and extinguish the valve V₂₈ and the contacts DA2 break the automatic stepping circuit of the uniselector ZRU. The contacts UA1 hold the relay UA and extinguish the valve V₂₉, and the contacts UA2 break the automatic stepping circuit of the uniselector ZRD.

Thus the wipers of the banks ZRD3 and ZRU3 are arrested on the bank contacts connected to the terminals T₁₀' and T₁₁' respectively. The pulses d₀ and u₁ are applied to these terminals respectively from the high frequency pulse generator. In the absence of a d₀ pulse the rectifier W₂₀ is conducting and hence the u₁ pulses are dropped across the resistor R₄₀. The occurrence of a d₀ pulse renders the rectifier W₂₀ nonconducting and hence the u₁ pulse occurring during each d₀ pulse passes to the contacts CD1 that is to say pulses in channel No. 1. These contacts close simultaneously with the opening of the automatic stepping circuit of the selectors and the pulses in channel No. 1 pass to the suppressor grids of the valves V₂₄ and V₂₅.

Thus unmodulated pulses of anode current flow in the valves V₂₄ and V₂₅ which are arranged to be normally non-conducting by the bias applied thereto from the terminals—GB₈ and—GB₁₀ respectively. The pulses passed by the valve V₂₅ are applied through the capacitor C₂₈ to the control grid of the valve V₂₆. Thus, pulses of anode current flow in this valve which is arranged to be normally non-conducting by the bias applied thereto from the terminal—GB₁₁. Thus the relay RB becomes energised and the contacts RB1 and RB4 thereof are operated.

The contacts RB3 put an earth on the terminal PI₂ and hence hold the relay K of Fig. 2 it being arranged that the contacts RB3 close about 1/2 second before the contacts L1 of Fig. 2 open. The contacts RB2 close and hold the relays DA and UA when the relay RQ becomes de-energised on the operation of the contacts RB3.

The contacts RB4 close and apply ringing voltage from the transformer XF₃ to the called subscriber's station. When the called subscriber answers the relay F becomes energised, the energising circuit being from earth through the battery BAT₃₃ the contacts F₃, the called subscriber's line, the contacts F₂, the relay winding F, the contacts RB4 and the secondary winding of the transformer XF₃ back to earth. The contacts RB1 and F₁ hold the relay F.

The relay RD then becomes energised, the energising circuit being from earth through the battery BAT₃₀, one winding of the relay RD, the contacts F₃, the called subscriber's line the contacts F₂ and the other winding of the relay RD back to earth.

The contacts Rd1 then apply the pulses in channel No. 1 through the valve V₃₁ to the terminal ASP₁ and thence through the metering and release junction (19 Fig. 1) to the terminal ASPO₁ of Fig. 3 (calling unit). The rectifier W₇ is rendered non-conducting thereby and permits the pulses in channel No. 1 from the terminal GP to appear at the control grid of the valve V₆. This valve then passes pulses of anode current through the relay winding D which becomes energised.

The contacts D₁ and D₂ operate and reverse the polarity of the terminals +O₁ and -O₁. This is for

signalling purposes as described on page 278 of Telephony, vol. II by Atkinson. The contacts D4 apply a pulse of current to the terminal PO₁ from the battery BAT₁₀, the relay contacts J1 being operated after the contacts D4 on de-energisation of the slow operating relay J by the opening of the contacts D3.

The pulse of current applied to the terminal PO₁ operates the meter M of Fig. 2 to record the establishment of the call.

The contacts D5 (Fig. 3) open and hence remove the earth from the terminal HO. Thus the relay H of Fig. 5 becomes de-energised. The contacts H2 open and hence the relay KF is de-energised, and thus the register is released and the uniselector CUF homes.

Speech voltages from the calling subscriber's station are transmitted through the transformer HY₁ to the control grid of the valve V₄ and there amplitude-modulate the pulses in channel No. 1 applied to the terminal GSP₁. These amplitude-modulated pulses pass through the GO speech junction to the called units.

Referring to Fig. 8 all pulses from the terminal GSPO₁ of the GO speech junction are passed to the control grid of the pentode V₂₅ which is gated by channel No. 1 pulses as previously described. Thus only the pulses in channel No. 1 pass to the transformer XF₂.

The primary winding is tuned by the capacitor C₃₀ to a periodicity of approximately twice the width of the pulses applied thereto from the valve V₂₅, and is heavily damped by the resistor R₁₉₄. The winding S₂XF₂ has more turns than the winding S₂XF₁ and hence provides a greater output voltage than S₂XF₁. The negative terminal of the source —GB₁₃ is arranged to be about five volts less negative than the negative terminal of the source —GB₁₂.

Assuming the charge in the capacitor C₃₁ to be such that the potential of the upper plate thereof in the drawing is between that of —GB₁₃ and —GB₁₂, the rectifiers W₁₆ to W₁₉ are non-conducting. When a pulse arrives at the primary winding of the transformer XF₂ from the valve V₂₅ the leading edge of the pulse shock excites the transformer. The first, and negative, half-cycle of the free oscillation is applied to the anode of W₁₆ which, therefore, remains non-conducting, and to the cathode of W₁₇ which becomes conducting and hence C₃₁ discharges through R₃₇ and W₁₇ until the potential of its upper plate in the drawing equals the potential of the negative terminal of the source —GB₁₂. Any further negative excursion at the cathode of W₁₇ is damped by W₁₈. Simultaneously W₁₉ becomes conducting and as a result the capacitor C₃₁ discharges further and its upper plate is left at a potential somewhat below that of the negative terminal of the source —GB₁₂.

Just as this negative half-cycle ends, the lagging edge of the pulse arrives and again the transformer XF₂ is shock-excited but this time in the opposite sense. The first, and positive, half-cycle of this second free oscillation has no effect on W₁₇ and W₁₈. The capacitor C₃₁ is charged, however, through W₁₆ to a value dependent upon the amplitude of the pulse applied to the transformer XF₂, and lying between the potentials of the negative terminals of the sources —GB₁₂ and —GB₁₃.

The damping provided by the resistor R₁₉₄ is arranged to be sufficient to prevent subsequent half-cycles from affecting the charge in the capacitor C₃₁.

Thus the capacitor C₃₁ presents relatively broad pulses to the valve V₂₇ in response to relatively narrow pulses passed by the valve V₂₅, the amplitude of the broad pulses being dependent upon the amplitude of the narrow pulses.

The broad amplitude-modulated pulses are demodulated by being passed through the low-pass filter FIL₂ and the speech voltages are passed through the transformer HY₂, the capacitors C₂₂ and C₂₃, the contacts F2 and F3, and the called subscriber's line circuit to the called subscriber's line.

Speech voltages from the called subscriber are passed through his line circuit, and the hybrid transformer HY₂

to the control grid of the pentode V₂₄. Here they serve to amplitude-modulate the pulses (in channel No. 1) applied from the anode of V₂₄ to the terminal RSP₂. These pulses are applied through the RETURN speech junction to the terminal RSPO₁ to Fig. 3 and thence to the control grid of the pentode V₅ which is gated by pulses in channel No. 1 applied to the suppressor grid from the terminal GP.

The transformer XF₁ in the anode circuit of the valve V₅, together with the capacitors C₇ and C₁₀, the resistors R₇ and R₁₉₅, and the rectifiers W₃ to W₆, function in the same manner as the transformer XF₂, capacitors C₃₀ and C₃₁, resistors R₃₇ and R₁₉₄, and rectifiers W₁₆ to W₁₉ of Fig. 8, to broaden the pulses passed by the valve V₅.

15 The broadened, amplitude-modulated pulses are passed through the valve V₃ and are demodulated by a low-pass Filter FIL₁. The speech voltages are applied through the transformer HY₁ and the calling subscribers line circuit to the calling subscriber's line.

20 The operation of the arrangement shown when a called subscriber is already engaged will now be described. When the called subscriber is engaged, the relay K in his line circuit (Fig. 2) is already energised and the junction of WX₂ and R₂₀₂ is connected through the relay contacts

25 K₆ to the terminal BJ₁. Thus the d' and u' pulses arriving at the terminal RTX in the channel intervals of channel No. 1464 in the present example are transmitted to the terminal BJ₁ and thence through the Busy junction to the terminal BJO in the register (Fig. 5) allotted to the calling subscriber.

30 Thus these pulses coincide with the d' and u' pulses applied from the terminal Rd'u' to the rectifier W₁₄ which is rendered non-conducting thereby. Thus the d' and u' pulses applied to the terminal BJO pass through the

35 capacitors C₁₃ and C₁₄ to the control grids of the valves V₇ and V₈. The d' pulse serves to strike the valve V₇ whose cathode potential rises. The rise in potential at the cathode of the valve V₇ is transmitted to the control grid of the valve V₈ but is arranged to be insufficient to

40 strike V₈. The u' pulse applied to the control grid of V₈ is arranged to provide sufficient extra potential to strike V₈. The relay BR is, therefore, energised. The contacts BR₁ close and hence earth the terminal BU₁. Referring to Fig. 3, when the terminal BU₁ is earthed the relay G becomes energised. The contacts G₁ hold the relay G and the contacts G₂ apply the busy tone to the calling subscribers line through the relay windings A and the calling subscriber's line circuit.

45 When a call is ended and the calling subscriber replaces his handset on its rest, the energising circuit for the relay A (Fig. 3) is broken. The relay contacts A₁ return to the position shown thus de-energising the relay B. The contacts B₁ remove the earth from the terminal PO₁. Thus the relay K (Fig. 2) becomes de-energised, and the 55 uniselector S homes. The calling unit is released and all relays return to their unoperated condition.

50 Thus the pulses arriving in channel No. 1 in this example at the terminal GSPO₁ of Fig. 8 cease and hence the relay RB becomes de-energised. The contacts RB₃ open, and the earth is removed from the terminal PI₂. Thus the relay K in the called subscriber's line circuit is released and the uniselector in this line circuit homes. The contacts RB₁ open and release the relay F (Fig. 8). The contacts RB₂ open and release the relays DA and UA.

60 Thus the contacts DA₂ and UA₂ close and the uniselectors ZRU and ZRD home. The called unit is then ready for use in making another call.

65 I claim:

1. An automatic telephone exchange comprising a first group of communication channels the number of channels in the group being small relatively to the number of subscribers connected to the exchange, a plurality of channel terminating means connected to terminate one end of the channels respectively, separate line terminating means terminating the subscribers' lines respectively in the ex-

change, means connecting the line terminating means to said channel terminating means, said line terminating means comprising means responsive to an initial calling signal from a calling subscriber to select a free one of said channel terminating means, a group of registers, allotting means connecting said registers and said channel terminating means to allot a register to a channel terminating means, a second group of communication channels extending from said registers to the said line terminating means respectively, the number of channels in said second group being equal to the number of said line terminating means, said registers comprising means responsive to a further calling signal representative of the number of a called subscriber to transmit in that one of the channels of the second group extending to the line terminating means of the called subscriber a signal to call said called subscriber, a further group of communication channels extending from said registers to said line terminating means respectively, said registers also comprising means responsive to said further calling signals to transmit to the line terminating means of the called subscriber a signal indicating the selected free one of said channel terminating means, further channel terminating means for terminating the other ends of the channels in said first group, and a plurality of control means connected between said line terminating means and said further channel terminating means, said line terminating means comprising selector apparatus responsive to said calling signals to select a free one of said control means and said control means being responsive to said signal indicating said selected free one of the first said channel terminating means to connect one of said further channel terminating means to the

same channel as the selected one of the first said channel terminating means and to connect the called line terminating means to the said one of the further channel terminating means.

- 5 2. An automatic telephone exchange according to claim 1, wherein the said first group of communication channels is a group of time-sharing pulse communication channels and each channel terminating means comprises a pulse modulator and a pulse demodulator.
- 10 3. An automatic telephone exchange according to claim 2, wherein the said second group of channels is a group of time-sharing pulse communication channels, a gate is provided in each of said line terminating means and means are provided for applying gating pulses of different phases to the gates in different ones of said line terminating means.
- 15 4. An automatic telephone exchange according to claim 3, wherein said further group of communication channels extending from said registers to said line terminating means respectively is a group of time-sharing pulse communication channels.
